(57) **CLAIM**

The ornamental design of the insulated growler for containing liquids, as shown and described.

DESCRIPTION

FIG. 1 is a perspective view of an insulated growler for containing liquids with the handle oriented away from the viewer at approximately 45° and with the lid closed;
FIG. 2 is a perspective view of an insulated growler for containing liquids with the handle oriented toward the viewer at approximately 45° and with the lid open;
FIG. 3 is a front view of the growler with the handle oriented behind the growler and hidden from view;
FIG. 4 is a rear view of the growler with the handle oriented toward the viewer in front of the growler;
FIG. 5 is a top view of the growler;
FIG. 6 is a bottom view of the growler; and,
FIG. 7 is a left side view of the growler which is a mirror image of the right side view of the growler.
